UNITED STATES PATENT OFFICE.

SCHUYLER E. FARNHAM, OF RACINE, WISCONSIN, ASSIGNOR OF ONE-FOURTH TO ROBERT W. HINDLEY, OF RACINE, WISCONSIN.

ADDRESSING-MACHINE.

SPECIFICATION forming part of Letters Patent No. 766,233, dated August 2, 1904.

Application filed September 8, 1903. Serial No. 172,193. (No model.)

To all whom it may concern:

Be it known that I, SCHUYLER E. FARNHAM, a citizen of the United States, and a resident of Racine, in the county of Racine and State 5 of Wisconsin, have invented certain new and useful Improvements in Addressing - Machines; and I do hereby declare that the following is a full, clear, and exact description thereof.

10 My invention has for its object to provide machines especially designed for mechanical addressing of newspapers, but which may be utilized to likewise address circulars, envelopes, and wrappers, said invention consisting 15 in what is hereinafter particularly set forth with reference to the accompanying drawings and subsequently claimed.

Figure 1 of the drawings represents a vertical longitudinal section of an addressing-machine in accordance with my invention, having portions thereof partly broken away; Fig. 2, a plan view of the machine, partly in horizontal section and having parts thereof broken; Fig. 3, a horizontal section view indicated by line 3 3 in the first figure; Figs. 4 and 5, vertical transverse section views respectively indicated by lines 4 4 and 5 5 in said first figure; Figs. 6 and 7, vertical longitudinal section views respectively indicated 30 by lines 6 6 and 7 7 in the fifth figure; Fig. 8, a detail partly-sectional view indicated by line 8 8 in the ninth figure; Fig. 9, a detail section view indicated by 9 9 in the second and eighth figures; Fig. 10, a section view indicated by line 10 10 in said eighth figure; Fig. 11, a partly-sectional elevation of a detail of the machine; Fig. 12, a detail partly-sectional view illustrating automatic closing of an electric circuit incidental to movement 40 of a galley of address matter having intermittent travel in the machine, and Fig. 13 a perspective view of a fragment of the galley.

Referring by letter to the drawings, A indicates a main shaft, for which the stand or 45 frame of the machine is provided with bearings, this stand or frame being of any suitable material and construction. A lever-controlled sliding clutch B is provided on the main shaft to be thrown in and out of en-

gagement with the clutch-hub of a driving-pulley C, that runs loose on said shaft when out of clutch with the same. The clutch-lever D is connected to a rod E, and by operating the rod the machine is put in and out of motion. Means hereinafter described are 55 provided for automatically stopping the machine under certain conditions.

A horizontal shaft F has bevel-gear connection with the main shaft A and an inclined shaft G, that is likewise connected to another horizontal shaft H, to which a wrist-wheel b is made fast. A link c connects the wrist-wheel with a horizontal slide I, having a vertical arm d, and a spring-controlled hook e is pivotally connected to said arm to have engagement with transverse notches in the upper faces of side bars of galleys J, containing inked address matter, the galleys being successively fed to a horizontal track constituting part of the machine. The reciprocative motion imparted to the slide I and hook e therewith results in an intermittent travel of a galley or galleys on the track, this motion being timed to move said galley or galleys forward one address-space while a vertically-recipro- 75 cative stamp hereinafter more particularly specified is on its upward movement.

The rear portion of the galley-track is at all times stationary; but a forward section K of said track has intermittent vertical reciprocation to effect the discharge of galleys one at a time onto a skid L, that has a horizontal extension at one side of the machine. Live galleys are placed on an inclined rack M at one side of the machine to slide onto the stationary rear portion of the horizontal track, and a weighted trip-lever N is provided at one end with a stop-lug f, that is normally in the path of the lowermost galley on said rack. The last galley fed to the horizontal track bears on one end of the trip-lever to hold the same in normal position; but when said galley clears said lever the latter has gravity tilt to permit its stop-lug f to clear the next galley on the rack M, and coincident with the slide of this 95 galley onto said horizontal track the aforesaid lever is automatically returned to normal position.

The section K of the horizontal galley-track is supported flush with the remainder of said track by spring-controlled latches *g*, and a slide-bar O is provided with cam-lugs *h*, that 5 operate to trip the latches against spring resistance. One end of the slide-bar is angularly bent to be in the path of the galley that is fed along the track-section K, and by the time said galley is full on said track-section said slide- 10 bar has been automatically adjusted in its guides against resistance of a suitably-arranged spring *i*, the result being a trip of the latches *h* and gravity descent of the aforesaid track-section.

15 Vertical recesses in a rail of the track-section K extend down into vertical appendages *j* of said rail, for which the machine-frame is provided with guides, and the upper ends of the beams of the skid L extend through said 20 recesses. The other rail of the track-section K is provided with a vertical appendage in the form of a rack-bar P, for which the machine-frame is provided with a guide, and this rack-bar meshes with a pinion Q, having a clutch-hub in sliding connection with the main shaft A to come in and out of engagement with a clutch R, fast on said shaft. A spanner S in 25 pivotal connection with the machine-frame straddles the rack-bar and engages annular grooves in the clutch-hub of the pinion Q, the forks of this spanner being respectively in the path of upper and lower cam-lugs *k m*, with which said rack-bar is provided. The track-section K being tripped to descend and dis- 30 charge a dead galley therefrom onto the skid L, the upper cam-lug *k* of the rack-bar operates on the spanner S to cause a throw of the pinion Q in the direction necessary to effect a clutch of same with the main shaft A, whereby 35 there is automatic return of said track-section to normal position, at which time the lower cam-lug *m* of said rack-bar operates on said spanner to throw said pinion out of clutch with 40 said shaft.

45 Trained on suitably-arranged rollers in the machine are upper and lower endless tapes T U in series transversely of the machine and between tapes, that together constitute what is hereinafter termed a "paper-runner." The 50 material to be addressed is carried piece by piece in successive order. The upper tapes T run on a feed-roller V, and the lower tapes U are trained on a similar roller W under the one aforesaid, the lower roller being journaled in 55 stationary bearings. The upper feed-roller V is journaled in boxes *n*, for which vertical guides are provided, and semi-elliptic spring X bears on the journal-boxes under tension of a set-screw *p*, adjustable in a bar of the 60 machine-frame. A journal of the lower feed-roller W is in bevel-gear connection with a vertical shaft Y, that has similar connection with the horizontal shaft F, and thus said feed-roller derives its motion from the main shaft

A of machine, the upper feed-roller being 65 driven by friction.

Newspapers or other material to be addressed are fed one by one between the tapes T U to be carried forward; but the travel of each is interrupted for a time by stop-fingers 70 *r*, that extend upward from a transverse bar Z, adjustably supported on levers A', one of which is connected by a link *s* with another lever, B', that is spring-controlled and in contact with a cam C, fast on the main shaft A of 75 the machine. At each revolution of the main shaft the cam C', acting on the lever B', causes a lift of the bar Z to bring the fingers *r* of same in the path of a paper traveling with the tapes T U, and coincident with this operation a stamp D', in connection with a vertically-reciprocatory cross-head E', is moved down to impact the paper on an address in an underlying galley that has been inked by any suitable means previous to its introduction to 80 the machine and is for the time being at rest on the horizontal track above specified. The cross-head E' is guided in the machine-frame and connected by a link *t* with a wrist-wheel F', with which the main shaft A is provided. 85

An address having been printed, there is automatic elevation of the stamp D', retraction of the stop-pins *r*, and continued travel of the paper, while at the same time the galley is moved forward one address-space. The 90 addressed papers discharge onto a slide *u* after passing the feed-rollers V W and pile on a carrier that is herein shown as being an endless apron G', trained transversely of the machine on rollers H' I', journaled in suitable 95 bearings. The roller I' is journaled in a yoke J', adjustable to regulate the tension of the 100 endless apron.

It is designed to print all the addresses of each destination successively and to have said 105 destination appear with the last address. Hence the matter in a galley or galleys is composed with this object in view, and the galley containing a destination line or lines is provided with a suitable striker or strikers *v*, 110 each of which is arranged to operate a spring-contact *w*, that is thereby put in touch with another contact *x* to close the circuit of an electromagnet K' at the time all the papers for a corresponding destination are delivered 115 in a stack on the apron G', the result being that an armature in connection with a pivotal latch L' is attracted by said electromagnet. This latch has in the meantime been engaged with a lug *y* of the shank of a spanner M', the fork 120 of which engages an annular groove of a clutch N' in sliding connection with a journal of the apron-roller H', and said latch being lifted the expansive force of a previously-compressed spring *z* operates to throw said clutch 125 into engagement with the clutch-hub of a bevel-gear pinion P', that is normally loose on the aforesaid roller-journal, and in mesh with

a bevel gear-wheel Q', fast on the vertical shaft Y, this wheel being provided with a cam-lug b', that operates to retract the spanner M' and parts in connection therewith against resistance of said spring, said spanner being then caught by the latch L' aforesaid. As a result of an operation of its drive-roller H' the apron G' has had sufficient motion to convey the addressed papers for one destination out of the way of those for another destination that are now being deposited on said apron. Fig. 12 illustrates the close of the electro-magnet-circuit at the time the third paper for one destination is being addressed, and at this time all the papers for another destination will have been stacked on the apron G' and moved toward a side of the machine clear of those being fed to said apron, that is now stationary.

20 The papers fed between the tapes TU pass between spring-contact terminals c' d' of the circuit of an electromagnet R', the armature of which is in connection with a pivotal latch S', that engages with a lug e' of the rod E when the latter is adjusted in its guides against resistance of a spring T' to start the machine. The spring-contact d' is stationary; but the one c' reciprocates with the stamp D', the result being that when there is proper printing of addresses on papers fed to the machine said contacts do not come into touch; but if there be a misprint of an address the aforesaid contacts will come together to cause energization of the electromagnet R', whereby 35 the latch S' is retracted and the rod E moved by recoil of the spring T' to automatically stop the machine.

While I have shown and described a practical construction and arrangement of parts 40 constituting a machine in accordance with my invention, the detail of said machine may be indefinitely varied without change of results or departure from the scope of said invention, that comprises in a single machine means 45 for feed of live galleyes of address matter to a track, intermittent travel of these galleyes, a paper-runner, paper-stop, means for impacting successive papers on address matter in a galley, discharge of dead galleyes, piling of 50 the addressed papers in readily-identified stacks according to different destinations and moving each stack out of the way of papers discharging from the feed to form another stack, and for stopping the machine in case of 55 misprint of an address.

Having thus described my invention, what I claim as new, and desire to secure by Letters Patent, is—

1. In an addressing-machine, a track, means 60 for traveling live galleyes of address matter on the track, and means by which an automatic gravity discharge of dead galleyes from the machine is effected.

2. In an addressing-machine, a track, a skid 65 under the forward portion of the track, means

for feeding live galleyes of address matter on said track, and means for delivering dead galleyes to the skid.

3. In an addressing-machine, a track having a vertically-reciprocatative section, means for traveling live galleyes of address matter on the track, a skid intercepting the reciprocatative track-section transversely of the same, and means for putting said track-section in motion to discharge a dead galley on the skid. 75

4. In an addressing-machine, a track having a gravity drop-section, means for traveling galleyes of address matter on the track, latch mechanism by which the drop-section of the track is held in normal position, latch trip 80 mechanism operative by contact therewith of the forward galley on said track-section, a skid arranged to receive a descending galley and means for restoring the aforesaid track-section to normal position. 85

5. In an addressing-machine, a track, means for intermittently traveling live galleyes of address matter on the track, a continuously-operating paper-runner, a stop reciprocatative to come in and out of the path of papers fed by 90 the runner, and means for impacting a stopped paper on contents of a stopped galley.

6. In an addressing-machine, means for intermittently traveling of galleyes of address matter, a paper-runner, a stop operative to 95 come in and out of the path of the papers, a reciprocatative stamp for impacting a stopped paper on contents of a galley when at rest, and means for automatically stopping the machine in case of a misprint. 100

7. In an addressing-machine, a continuously-operating paper-runner, a stop reciprocatative to come in and out of the path of successively-fed papers, a track, and means by which galleyes of address matter are intermittently traveled on the track, a reciprocatative stamp for impacting a stopped paper on an address in an adjacent galley then at rest, a carrier on which addressed papers are delivered, and means by which the carrier is put 110 in motion for a limited time at predetermined intervals.

8. In an addressing-machine, a continuously-operating paper-runner, a stop reciprocative to come in and out of the path of successively-fed papers, a track, means by which galleyes of address matter are intermittently traveled on the track and discharged therefrom, a reciprocatative stamp for impacting a stopped paper on an address in an adjacent 115 galley then at rest, a carrier on which addressed papers are delivered, and means by which the carrier is put in motion for a limited time at predetermined intervals. 120

9. In an addressing-machine, a continuously-operating paper-runner, a stop reciprocative to come in and out of the path of successively-fed papers, a rack and track, means governing feed of galleyes of address matter from rack to track, means for intermit- 125 130

tently traveling said galley on said track, a reciprocal stamp for impacting a stopped paper on an address in an adjacent galley then at rest, a carrier on which addressed papers are delivered, and means by which the carrier is put in motion for a limited time at predetermined intervals.

5 In testimony that I claim the foregoing I

have hereunto set my hand, at Milwaukee, in the county of Milwaukee and State of Wisconsin, in the presence of two witnesses.

SCHUYLER E. FARNHAM.
